UNITED STATES PATENT OFFICE.

CORNELIUS SULLIVAN, OF CLEVELAND, OHIO.

DESIGN FOR A SYRINGE-PIPE.

SPECIFICATION forming part of Design No. 29,765, dated December 6, 1898.

Application filed September 12, 1898. Serial No. 690,803. Term of patent 14 years.

To all whom it may concern:

Be it known that I, CORNELIUS SULLIVAN, a citizen of the United States of America, and a resident of Cleveland, county of Cuyahoga, 5 State of Ohio, have invented and produced a Design for a Syringe-Pipe, of which the following is a specification, reference being had to the accompanying drawings, forming part thereof.

10 Figure 1 is a side view of the syringe-pipe, showing my new design. Fig. 2 is an edge view thereof. Fig. 3 is a transverse section on line X X, Fig. 1.

15 The leading or characteristic feature of the design comprises the shape or configuration of the entire article, as shown in the accompanying drawings.

20 The entire design is somewhat curved or crescent - shaped, the body portion being pierced by a somewhat crescent shaped open-

ing 2. The separated central portions are cylindrical in shape, as seen in Fig. 3 in section. The terminal point 3 is also cylindrical in shape and inwardly curved at 4. The other extremity is gourd-shaped and provided with 25 convex corrugations tapering toward either end. Small circular openings 6 are shown in the depressions between the corrugations.

Having described my invention, what I claim as new, and desire to secure by Letters 30 Patent, is—

The design for a syringe-pipe as herein shown and described.

Signed by me, at Cleveland, Ohio, this 9th day of September, 1898.

CORNELIUS SULLIVAN.
